N. B. HURD

DOOR LOCK

Filed Jan. 26, 1924

UNITED STATES PATENT OFFICE.

NORMAN B. HURD, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

DOOR LOCK.

Application filed January 26, 1924. Serial No. 688,647.

To all whom it may concern:

Be it known that I, NORMAN B. HURD, a citizen of the United States of America, residing at New Britain, Connecticut, have invented new and useful Improvements in Door Locks, of which the following is a specification.

My invention relates to door locks and latches, and consists in providing a new and improved form of dogging mechanism for the latch bolt and stop work by which, when the door is closed and the stop work is "on", the latch and stop work will be positively blocked against reversion from the outside, and yet said latch may be retracted by the proper means, such as a key for entrance from the outside, or by a knob on the inside of the door.

In the accompanying drawings—

Fig. 1 is a side elevation of the lock and latch mechanism with the cap removed.

Fig. 2 is a front elevation.

Fig. 3 is a section on the line 3—3 of Fig. 1.

Fig. 4 is a section on the line 4—4 of Fig. 1.

1 represents the usual face plate through which protrudes a spring latch bolt 2. The usual case is connected to the rear of this face plate. 3—3^a are the plungers of the so-called "stop work" by which the roll-back for the outside knob may be dogged so that the door cannot be opened from the outside excepting by means of a suitable key. 4

5 represents a roll-back for the outside knob, 5 represents a key-controlled roll-back ordinarily carried by a cylinder lock 6 at the outdoor side of the lock. 7 represents the tail of the latch bolt 2. 8 represents a coil

40 spring mounted freely on the latch bolt tail and functioning to normally press the latch 2 outwardly. 9 represents a shoulder or abutment on the rear end of the tail 7. 10 is the latch-retracting lever, pivoted at 11, one

45 end of said lever bearing against the abutment 9 and the other end being adapted for engagement by the key roll-back 5. 12 is another latch-retracting lever, pivoted at 13. 14 is a roll-back for operation by an

50 indoor knob. This roll-back 14, as shown in Fig. 1, usually overlies the roll-back 4, which latter is controlled by the outdoor knob. I have not shown the ordinary inner

55 and outer knobs and the corresponding spin- dles for coaction with the two roll-backs 4

and 14, since such details are very well known and require no illustration.

The stop-work plungers are of the conventional type and the same are connected within the lock case by the usual walking-beam, 60 so that when one plunger is pushed in, the other will be pushed out. As shown in Fig. 1, the stop-work is in the "on" position, dogging the outer knob roll-back 4; that is to say, the rear end of the plunger 3^a has a nose 65 16 which projects into a recess on the hub of the roll-back 4, thereby preventing it from being turned. When the plunger 3 is pushed in, the plunger 3^a will be moved out, so that the nose 16 will be withdrawn from engagement with the roll-back 4, freeing the latter.

17 is a dogging lever, which functions to dog the latch bolt 2 and the stop-work plunger 3 when said lever stands in the position shown in solid lines in Fig. 1. This dogging lever 17 is pivoted at 18 and its lower edge rests upon a pin 19 on the latch-retracting lever 10. There is an incline on the lower edge of the dogging lever 17, to the rear of the pin 19, so that, when the lever 10, is swung back it will quickly lift the dogging lever 17 to the dotted line position. It will be observed that the forward end of the dogging lever 17 is provided with two noses 85 20—21. The upper nose 20 normally stands to the rear of the inner end of the plunger 3, when the stop-work is "on", while the nose 21 at such a time stands to the rear of a lever 22 carried by the latch bolt 2. Hence, 90 at such a time it will be impossible to push in the button 3 or the latch 2 by employing force against the outer end of either of the same. The lever 22 is pivoted at 23 in a slotted portion of the latch bolt 2. The 95 outer end 24 of the lever 22 is exposed on the beveled side of the latch bolt, and normally projects slightly above the beveled face, as seen in Fig. 3. 25 is a spring for holding the said lever 22 normally in the position indicated in solid lines. The upper surface of the inner end of the lever 22 is provided at one side with a beveled incline 26, which incline, when the lever is tilted to the dotted line position indicated in Fig. 3, will be positioned directly in front of the nose. This permits the latch to be pushed back as the door closes even if the stop-work has been put "on." For example, assuming the stop-work is "on" and the door is closing. As 100 105 110

it is just about to close the outer end 24 of the lever 22 will encounter the edge of the usual strike plate 27 and be repressed thereby. This will cause the incline 26 to face up with the nose 21. As the door continues to close the latch 2 encounters said strike plate and is repressed thereby this being permitted since the incline 26 will slide under the dogging lever 17 and will momentarily lift the same. As soon as the end 24 of the lever reaches the keeper socket in the strike plate, said lever 22 will be swung back to the position indicated in dotted lines, and this will serve to hold the dogging lever 17 elevated until the latch bolt springs forward into said keeper opening of the strike plate whereupon the outer end of the lever 24 will release the dogging lever 17, which will then move down into the dogging position under the influence of the spring 28. 29 is the usual spring for the latch retracting lever 12. 30 is the usual detent spring for the stop-work plunger 3^a which serves to frictionally hold the stop-work in the "on" or "off" position.

Operation.—The operation is plain from the above description. When the stop-work is "off" the inner end of the plunger 3 will stand under the nose 20, of the dogging lever 17 holding the same in the non-dogging position, at which time the latch may be freely retracted by either the inner or outer door knob. When the plunger 3^a is pushed in, the dogging lever 17 drops to the operative position, so that, at such a time, the door can be opened by the use of the inside knob, or by a key capable of operating the roll-back 5. It will be noted that in effect a loop movement occurs between the rear end of the lever 22, and the end 21 of the dogging lever whenever the dogging mechanism is "on" and the latch is retracted. By this movement the jamming and breakage of parts is avoided.

I have shown my invention in its preferred form but I am aware that changes may be made without avoiding the scope of the appended claims or the spirit of the invention.

I claim:

1. In a door lock, a spring latch bolt, a knob-controlled roll-back and a key-controlled roll-back, both operable from the outdoor side of said lock to retract said latch, a stop-work mechanism operable in one position to hold the said knob-controlled roll-back against movement, a dogging de-

vice to dog both the latch and the stop-work when the latter is in said roll-back holding position, a lever pivoted on the latch bolt, the inner end co-acting with said dogging device when in one position to block the repression of the latch, and co-acting with said dogging device when in another position to move the latter out of the latch dogging position to permit the latch to be repressed by strike plate engagement as the door is closing.

2. In a door lock, a spring latch bolt, a knob-controlled roll-back and a key-controlled roll-back, both operable from the outdoor side of said lock to retract said latch, a stop-work mechanism operable in one position to hold the said knob-controlled roll-back against movement, a dogging device to dog both the latch and the stop-work when the latter is in said roll-back holding position, and a lever pivoted on the latch bolt, the inner end co-acting with said dogging device when in one position to block the repression of the latch, and co-acting with said dogging device when in another position to move the latter out of the latch dogging position to permit the latch to be repressed by strike plate engagement as the door is closing, said pivoted lever having a projection adjacent to the outer end of the latch for engagement with the strike plate in advance of said latch.

3. In a door lock, a spring latch bolt, a knob-controlled roll-back and a key-controlled roll-back, both operable from the outdoor side of said lock to retract said latch, a stop-work mechanism operable in one position to hold the said knob-controlled roll-back against movement, a dogging device to dog both the latch and the stop-work when the latter is in said roll-back holding position, and a lever pivoted on the latch bolt, the inner end co-acting with said dogging device when in one position to block the repression of the latch, and co-acting with said dogging device when in another position to move the latter out of the latch dogging position to permit the latch to be repressed by strike plate engagement as the door is closing, the inner end of said lever having an incline on one side of its upper face, said incline facing said dogging lever when the door is closing and the strike plate is encountered.

NORMAN B. HURD.
